RAILWAY SWITCH OPERATING APPARATUS

Herbert L. Bone, Pittsburgh, Pa., assignor to The Union Switch & Signal Company, Swissvale, Pa., a corporation of Pennsylvania

Application November 27, 1935, Serial No. 51,855

9 Claims. (Cl. 246—257)

My invention relates to railway switch operating apparatus, and has for an object the provision of a novel and improved circuit controlling mechanism, commonly known as a point detector, 5 for detecting any failure of the switch points to occupy their proper positions relative to the fixed rails in either extreme position of the switch.

A further object of my invention is the provision of a latch mechanism which, in the event 10 that the contacts of the circuit controlling mechanism are improperly forced open, as by a train trailing the switch when the switch points are locked in either extreme position, is effective to latch the contacts in their open positions until 15 the latch mechanism is manually operated to release the contacts.

A still further object of my invention is the provision of a circuit controlling mechanism which can be applied with a minimum amount of 20 effort to switch operating apparatus which is already in service.

Other objects of my invention will appear as the description proceeds.

The circuit controlling mechanism set forth in 25 my present application is somewhat similar to that set forth in my prior copending application, Serial No. 665,914 filed on April 13, 1933, for Railway switch operating apparatus, and the said copending application contains claims which 30 cover broadly certain features of the invention described in my present application.

I will describe one form of apparatus embodying my invention, and will then point out the novel features thereof in claims.

35 In the accompanying drawings, Fig. 1 is a top plan view showing a railway switch A actuated by a switch operating mechanism B provided with a point detector mechanism M embodying my invention. Fig. 2 is an enlarged top plan view of a portion of the switch operating mechanism B shown in Fig. 1 with the circuit controller C and point detector mechanism M removed to better illustrate the construction of the parts. 40 Fig. 3 is a front view partly in elevation and partly in section of a portion of the apparatus shown in Fig. 1. Fig. 4 is an enlarged righthand side view, with cover removed, of the point detector mechanism M shown in Fig. 1. Fig. 5 is a top view partly in section, and partly in elevation, of the point detector mechanism M shown in Fig. 4. Fig. 6 is a sectional view taken substantially on the line VI—VI of Fig. 4.

Similar reference characters refer to similar parts in each of the several views.

55 Referring first to Fig. 1, the reference char-

acter A designates a railway switch comprising as usual two fixed rails 1 and 1^a and two movable switch points 2 and 2^a. The fixed rails 1 and 1^a are laid on tie plates 3 and are secured to cross-ties 4 in the usual manner. The switch points 2 and 2^a are connected together by a front rod 5, a head rod 6, and a tie rod 7, and may be moved into a normal or a reverse position by means of a switch operating mechanism B which is connected with the head rod 6 through the medium of an operating rod 8 and the usual switch basket 9. When the switch occupies its normal position, in which position it is shown in Fig. 1, the switch point 2 engages the fixed rail 1 and the switch point 2^a is spaced a predetermined distance from 15 the fixed rail 1^a. When the switch is reversed, however, the switch point 2^a then engages the fixed rail 1^a and the switch point 2 is spaced from the fixed rail 1.

The switch operating mechanism B is mounted 20 on a bed plate 10 which is secured to the ties 4 adjacent the outer side of the rail 1, and, in the form here shown, this mechanism comprises a base plate 11 (see Figs. 2 and 3) bolted to the bed plate 10, and carrying a longitudinally movable slide bar 12 consisting of an upper bar 12^a and a lower bar 12^b secured together in superposed parallel spaced relation. The slide bar 12 is guided between rollers journaled on studs which project upwardly from the base plate, and 30 is adapted to be reciprocated between two extreme positions, by any suitable means, here shown as a fluid pressure motor 13. A roller 14 is rotatably mounted between the bars 12^a and 12^b, and this roller coacts with an alligator jaw 15 which is 35 journaled at its lower end in the base plate 10, and at its upper end in the base 16 of a casing 17 which houses the usual indication circuit controller C. The casing 17 is bolted to the base plate 11, and serves not only as a housing for the 40 circuit controller, but also to prevent vertical displacement of the slide bar 12 between its roller guides. The alligator jaw 15 is operatively connected with the previously described operating rod 8 in the usual and well known manner. 45

The circuit controller C is of well known construction, and is adapted to be operated by a motion plate 64 secured to the top of a slide bar 12. This circuit controller forms no part of my present invention, and need not, therefore, be described herein. It should be pointed out, however, that the point detector mechanism M embodying my present invention, which mechanism I will describe shortly, is intended to be attached 50 to switch operating mechanisms of the type de- 55

scribed which are equipped with circuit controllers of the type shown, or of a similar type, and the available space within which the point detector mechanism has to be confined and the 5 manner in which this mechanism has to be secured to the bed plate 10, is limited to a large extent by the presence of the circuit controller C. Furthermore, the point detector mechanism is adapted to be operated by the same motion 10 plate 64 which operates the circuit controller.

In addition to carrying the roller 14 the slide bar 12 carries two locking dogs 18 and 19 (see Fig. 3) which are attached to the upper and lower bars 12^a and 12^b, respectively, and which 15 cooperate with suitable notches 18^a and 19^a, respectively, formed in an adjustable lock rod L. The lock rod L is of the usual and well known construction, and is connected to the front rod 5 of the switch A in the usual manner. The apparatus which has thus far been described is in widespread use, and its operation is well understood, so that for purposes of my present invention, it is believed that the following brief 20 description of this apparatus will be sufficient.

25 When the slide bar 12 occupies its extreme normal position in which position it is shown in the drawings, the switch points are held in their normal positions by engagement of the roller 14 with the right hand side of the alligator jaw 15, and under these conditions, the locking dog 18 enters the notch 18^a in the lock rod L and locks the switch points in their normal positions. When, however, the slide bar is moved from its 30 normal extreme position to its reverse extreme position, the first part of the movement of the slide bar withdraws the locking dog 18 from the notch 18^a in the lock rod L to unlock the switch, the intermediate part of the movement of the slide bar causes the switch points to be moved 35 to the extreme position opposite to that in which they are shown in Fig. 1, and the final part of the movement of the slide bar moves the locking dog 19 into engagement with the notch 19^a in the lock rod L to lock the switch points in 40 their reverse positions. The operation of the apparatus when the slide bar 12 is subsequently restored to its extreme normal position is exactly the reverse of that just described, and will be obvious from an inspection of the drawing.

45 The point detector mechanism M embodying my present invention is mounted in a suitable casing 22 which straddles the slide bar 12 adjacent the right hand end of the circuit controller C as viewed in Figs. 1 and 3. This casing is bolted to the bed plate 10 by means of bolts 23, and is provided at the side which is farthest away 50 from the circuit controller C with a removable cover 24 held in place by thumb screws 25, whereby convenient access to the interior of the casing 55 22 for the purpose of inspection or repair of the mechanism may be had. Formed in the casing near the top of the casing are two tubular openings 26 through which electrical conductors may be brought into the casing. One or the other of 60 the openings 26 will usually be closed by a suitable closure member not shown, and the remaining one of these openings will usually be connected with the conduit opening 27 in the housing 65 of the circuit controller C (see Fig. 3), by means of a flexible conduit 28 and a special adapter housing 29, to protect the electrical conductors which will be led from the circuit controller to the point detector mechanism. The special adapter housing 29 is so constructed that 70 it may be conveniently attached to the casing 17

of the circuit controller C adjacent the conduit opening 27, and is provided with an opening 30 to receive the usual flexible conduit 31, as shown in Fig. 3.

Disposed within the casing 22 on opposite sides 5 of the slide bar 12 are two sets S¹ and S² of point detector contacts, each set of which, as here shown, comprises two flexible contact fingers 33 and 34 which cooperate respectively with two fixed contact fingers 35 and 36 to form contacts 10 33-35 and 34-36. The contact fingers of each set are clamped by means of bolts 37 between insulating blocks 38, and the insulating blocks 38, in turn, are clamped between two angle brackets 39 and 40 which are secured by bolts 41 and 15 42 to bosses 43 and 44 formed on the rear wall 22^a of the casing 22. The bolts 37 extend through clearance holes in the contact fingers and are insulated from the contact fingers by means of insulating sleeves 45. Terminal straps 46 are 20 clamped against one side of each contact finger, and each strap is provided at its outer end with an enlarged portion having a screw-threaded hole which receives a terminal screw 47, whereby electrical connection with the contact fingers may 25 be conveniently made.

The contacts of the two sets S¹ and S² of contacts are operated by means of two bell crank levers 48 and 49, each comprising a horizontal leg a and a vertical leg b. These bell crank levers 30 are pivotally supported on pins 50 and 51 secured to the rear wall 22^a of the casing 22, and the short leg of each lever is provided at its outer end with a laterally projecting pin 57 which cooperates with an open end slot 58 formed in a 35 metal clip 59 clamped between the lower ends of a pair of laterally spaced contact operating links 60. The contact operating links 60 are of insulating material, and are operatively connected with the free ends of the flexible contact fingers 40 33 and 34 of the associated set of contacts by means of transverse pins 63 which are mounted 45 in the operating links, and which extend with some clearance through circular return bends 33^a and 34^a formed on the ends of the contact fingers 45 33 and 34, respectively.

The bell crank levers 48 and 49 are controlled 50 jointly by a point detector rod D and by the motion plate 64. The point detector rod D is slidably mounted in the casing 22, and as shown in Fig. 1, is attached by means of a link 65 and a bolt member 66 to the movable rail 2 of the switch A. Formed in the point detector rod D is a notch 67 (see Fig. 4) which aligns with a roller 68 secured to the arm a of the bell crank 55 lever 48 when and only when the switch A occupies its extreme normal position and the switch point 2 is in close engagement with the fixed rail 1, and with a roller 69 secured to arm b of the bell crank lever 49 when and only when the switch 60 occupies its full reverse position and the switch point 2^a is in close engagement with the fixed rail 1^a. The parts are so proportioned that when either roller 68 or 69 is in the notch 67, the contacts controlled thereby will be closed, but that, 65 when either roller 68 or 69 is forced out of the notch 67, the contacts controlled by such roller will be open.

The bell crank levers 48 and 49 are operatively 70 connected with the motion plate 64 to be oscillated thereby in unison in the following manner: The leg b of the bell crank lever 48 is provided adjacent its upper end with a hole 70 which receives the shank of an eyebolt 71 with some clearance, and surrounding the eyebolt be- 75

tween its eye 71^a and the associated arm b is a compressed coil spring 72 which constantly biases the eyebolt to the relative position with respect to the arm in which the wedge-shaped inner face of a nut 73 which is screwed onto the end of the eyebolt opposite to the eye engages the arm b within a V-shaped notch 74 . The leg b of the bell crank lever 49 is similarly provided adjacent its upper end with a hole 75 which receives the shank of an eyebolt 76 with some clearance, and surrounding the eyebolt 76 between its eye 76^a and the associated arm b is a compressed coil spring 77 which constantly biases the eyebolt 76 to the relative position with respect to the arm b in which the wedge-shaped inner face of a nut 78 which is screwed onto the end of this eyebolt opposite to the eye engages the arm b within a V-shaped notch 79 . The eyes of both eyebolts 71 and 76 are pivoted on an up-standing pin 80 secured to one end of a horizontal lever 81 which is pivoted intermediate its ends on a pin 82 secured to a horizontal lug 22^b formed on the casing 22 directly above the slide bar 12 . The free end of the lever 81 is formed with a depending cam follower 83 which extends into, and cooperates with, a cam slot 84 formed in the motion plate 64 . As best seen in Fig. 2, the cam slot 84 is provided with a central portion 84^a which extends parallel to the direction of movement of the motion plate, and with oppositely offset end portions 84^b and 84^c which also extend parallel to the direction of movement of the motion plate and which are connected with the central portion 84^a by means of intermediate connecting portions 84^d and 84^e which extend at an angle to the direction of movement of the motion plate and which are parallel to each other.

The lengths of the various portions of the cam slot 84 are such, and the parts are so proportioned, that the cam follower 83 will engage the cam slot at the end portion 84^b or 84^c according as the slide bar occupies its extreme normal or its extreme reverse position, but that, when the slide bar is moved from its normal position to its reverse position, the cam follower 83 will be forced out of the end portion 84^b and into the central portion 84^a before the locking dog 18 becomes completely withdrawn from the notches 18^a in the lock rod L and will subsequently remain in the central portion 84^a until after the locking dog 19 has partly entered the notches 19^a in the lock rod L , and that, when the slide bar is moved from its reverse position to its normal position, the cam follower 83 will be forced out of the end portion 84^c and into the central portion 84^a before the locking dog 19 has become completely withdrawn from the notches 19^a in the lock rod L and will subsequently remain in the central portion 84^a until after the dog 18 has partly entered the notches 18^a . The parts are further so proportioned that when the cam follower 83 engages the cam slot 84 at the end portion 84^b , the bell crank lever 48 will be biased by the spring 72 to a normal extreme position in which the roller 68 will enter the 67 in the point detector rod D if this notch then aligns with the roller, and the bell crank lever 49 will be held by the eyebolt 76 and nut 78 in a normal extreme position in which the roller 69 is moved some distance away from the point detector rod, and that, when the cam follower 83 engages the cam slot at the end portion 84^c , the bell crank lever 49 will then be biased by the spring 77 to a reverse position in which the roller 69 will enter the notch 67 in the point detector rod

D if this notch then aligns with the roller and the bell crank lever 48 will be held by the eyebolt 71 and nut 73 in a reverse extreme position in which the roller 68 is moved some distance away from the point detector rod, but that when the cam follower engages the cam slot 84 at the central portion 84^a , both bell crank levers 48 and 49 will then be held by the eyebolts 71 and 76 and associated nuts 73 and 78 in intermediate positions in which the rollers 68 and 69 are just clear of the point detector rod. With the parts constructed and proportioned in the manner just described, it will be obvious that during movement of the slide bar from one extreme position to the other, the bell crank levers will normally move in unison.

Mounted in the arm b of the bell crank lever 49 is an adjustable stop screw 90 which cooperates with a portion of the case 22 to limit the position to which the bell crank lever 49 can rotate, in a counterclockwise direction, to that to which this lever is moved by the eyebolt 76 , and nut 78 when the cam follower 83 is within the portion 84^b of the cam slot 84 , and mounted in the arm b of the bell crank lever 48 in a similar adjustable stop screw 91 which cooperates with a portion of the case 22 to limit the position to which the bell crank lever 48 can rotate, in a clockwise direction, to that to which this lever is moved by the eyebolt 71 and nut 73 when the cam follower 83 is within the portion 84^c of the cam slot 84 .

The operation, as a whole, of the portion of the apparatus thus far described is as follows: As shown in the drawings, the slide bar 12 occupies its extreme normal position, and the switch points 2 and 2^a likewise occupy their extreme normal positions, so that the switch point 2 is held tightly against the associated fixed rail 1 . Under these conditions, the recess 67 in the point detector rod D aligns with the roller 68 of the bell crank lever 48 and the cam follower 83 on the lever 81 engages the cam slot 84 at the end portion 84^b , and as a result, both bell crank levers occupy their normal extreme positions. The contacts $33-35$ and $34-36$ of the set S^1 of contacts are therefore closed, while the contacts $33-35$ and $34-36$ of the other set of contacts are open.

I will now assume that with the parts in the positions just described, the slide bar 12 is moved from its extreme normal position to its extreme reverse position to move the switch points from their normal positions to their reverse positions. During the first or unlocking part of this movement of the slide bar, no motion of the switch points takes place for the reasons pointed out hereinbefore, but during the corresponding part of the resultant movement of the motion plate 64 , the cam follower 83 is forced out of the end portion 84^b of the cam slot 84 and into the straight central portion 84^a , thus causing the bell crank levers 48 and 49 to be rotated from their extreme normal positions in which they are shown in Fig. 4 to their intermediate positions. As was previously pointed out, when the bell crank levers are rotated to their intermediate positions, the contacts of both sets S^1 and S^2 of contacts are open and both rollers 68 and 69 occupy positions in which they are just clear of the point detector rod D . During the intermediate part of the movement of the slide bar, that is to say, during that part of the movement which causes the shifting of the switch points, the cam follower 83 will continue to engage the slide bar at the portion 84^a of the cam slot 84 , and it will be apparent, therefore, that the resultant movement of the

point detector rod D which takes place due to the reversal of the switch points will have no effect on the point detector mechanism. When the intermediate part of the movement of the slide bar has been completed and the final or locking part of the movement starts to take place, the cam follower 83 will move out of the straight central portion of the cam slot 84 and into the inclined portion 84^c, and just before the final locking part of the movement of the slide bar becomes completed, the cam follower 83 will enter the straight end portion 84^c of the cam slot. The movement of the cam follower out of the central portion 84^a of the cam slot and into the end portion 84^c will act through the eyebolt 71 and nut 73 to positively rotate the bell crank lever 48 in a clockwise direction from its intermediate position to its reverse extreme position, and will also act through the spring 71 to exert a force on the bell crank lever 49 which force biases this bell crank lever toward its reverse extreme position. When the bell crank lever 49 becomes biased to its reverse extreme position under these conditions the point detector rod D will have been moved to the position in which the notch 67 aligns with the roller 69 unless the switch points have been damaged or are out of adjustment, and assuming that the notch 67 is then in alignment with the roller 69 as will normally be the case, the bell crank lever will move to its reverse position due to the bias of the spring 71 and will thus cause contacts 33-35 and 34-35 of the set S² of contacts to become closed. The contacts 33-35 and 34-36 of the set S¹ of contacts, however, will remain open for reasons which are obvious.

When the slide bar 12 is in its extreme reverse position and the switch points are in their full reverse positions, if the slide bar is then restored to its extreme normal positions to restore the switch points to their normal positions, the operation of the apparatus will be exactly the reverse of that just described, and it is believed, therefore, that this operation will be apparent from the foregoing and from an inspection of the drawings without further description.

I will now assume that the parts are in the positions in which they are shown in the drawings and that a train trails the switch. Under these conditions, while the train is trailing the switch, the switch points will be displaced from their normal positions a certain amount by the wheels of the train, and this displacement will cause the point detector rod D to move toward the right, as viewed in Fig. 4, an amount which depends upon the amount of movement of the closed point, that is, the point 2. This movement of the point detector rod will cause the bevel face of the notch 67 in the point detector rod to engage roller 68 and will thus rotate bell crank lever 48 in a clockwise direction, as viewed in Fig. 4, in opposition to the bias of the spring 72. This rotation of the bell crank lever, in turn, will open contacts 33-35 and 34-36 of the set S¹ of contacts, thereby giving an indication that the train is trailing the switch, and that the points are displaced from their normal positions. When the train has completely trailed the switch, the displacing force on the switch points will, of course, be removed, and the points will then tend to spring back toward their normal positions. The movement of the points toward their normal positions will move the point detector rod D toward the left, as viewed in Fig. 4, and if the amount of this movement is sufficient to permit the roller 68 to fully

reenter the notch 67, the spring 72 will restore the bell crank lever 48 to its extreme normal position in which it is shown in Fig. 4, thereby restoring the contacts of the set S¹ of contacts to their normal closed positions. If, however, the switch points are so badly damaged by the trailing train that the movement of the point detector rod is insufficient to permit the roller 68 to fully enter the recess 67, or to enter it at all, the spring 72 will act to return the bell crank lever to such a position as the position in which the roller 68 engages the point detector rod will permit.

I will next assume that the slide bar 12 has been moved to its extreme reverse position so that the switch points are in their full reverse positions, and that a train trails the switch. Under these conditions, while the train is trailing the switch, the point detector rod D will be moved toward the left, as viewed in Fig. 4, and this movement of the point detector rod will cause the right-hand beveled face of the notch 67 to cooperate with the roller 69 in such manner that the bell crank lever 49 will be rotated in a counterclockwise direction, as viewed in Fig. 4, toward its intermediate position, in opposition to the bias of spring 71, thereby causing the contacts of the set S² to become opened. After the train has completely trailed the switch, if the switch points spring back toward their full reverse positions far enough to permit the roller 69 to completely reenter notch 67, spring 71 will act to restore the bell crank lever 49 to its full reverse position, but if the switch points do not spring back toward their full reverse positions far enough to permit the roller 69 to fully enter the recess 67, or to enter it at all, the bell crank lever will be retained in such position as the position in which the roller engages the point detector rod will permit.

It is desirable to insure that after a train has trailed the switch the point detector contacts will be retained in their open positions until they are manually released even though the point detector rod returns to a position which would permit these contacts to become closed. The reason for this is that it is necessary for clearance reasons to connect the point detector rod to the switch points some distance below the top of the points where, due to the rolling of the points during the trailing, the amount of movement of the points may not be more than one-half of that occurring at the top of the points, and as a result, the tendency of the points to spring back toward their original positions after the trailing train has passed the switch, may result in the final displacement of the point detector rod being very little, if any, more than the displacement which would correspond to the maximum permissible opening of the closed point, which opening is the setting at which the point detector contacts become opened, while the opening of the closed point at the top might be sufficient to be dangerous. For the purpose of retaining the contacts in their open positions after they have once been opened by a trailing train, I provide a latching device E which I will now describe. As here shown, this latching device comprises an adjustable latch rod 85, one end of which is pivotally attached to the upper end of the arm b of the bell crank lever 49, and the other end of which is provided with an enlarged latch head 86 which cooperates with an open end slot 87 formed in the upper end of the arm b of the bell crank lever 48. The latch

rod 85 is so adjusted that when the bell crank levers occupy the relative positions which they normally occupy, that is to say, the positions which they occupy when all parts are in proper adjustment and no train is trailing the switch, the latch 86 will engage the bell crank lever within the slot 87 in the manner shown in Fig. 4, but that, when the bell crank levers occupy the relative positions which they occupy when one of the rollers 68 or 69 is forced part way out of the notch 67 in the point detector rod D due to a train trailing the switch, the latch head 86 and arm b of bell crank lever 48 will then be moved to such relative positions that the righthand side of the latch head, as viewed in Fig. 4, will be clear of the lefthand side of the arm b of the bell crank lever 48. The latch rod 85 is biased by gravity and by a spring 88 to a downward position in which the latch head, or latch rod, as the case may be, is in engagement with the bottom of the slot 87.

With the latching device E constructed in the manner just described it will be apparent that during reversal of the switch points due to operation of the slide bar from one extreme position to the other, the latching device E will have no effect on the point detector mechanism, since the bell crank levers 48 and 49 move in unison under these conditions, and the circuit controller will therefore function in the manner previously described. When, however, a train trails the switch, if the resultant displacement of the switch points is sufficient to cause one or the other of the rollers 68 or 69 to be forced part way out of the recess 67 in the point detector rod D due to engagement of such roller with one or the other of the bevel faces of the notch 67, the consequent rotation of the bell crank lever 48 or 49, as the case may be, will move the latch head 86 and arm b of bell crank lever 48 to such relative positions that the righthand side of the latch head, as viewed in Fig. 4, is clear of the lefthand side of the arm b of the bell crank lever 48, and when this happens, the spring 88 will force the latch rod downwardly to a latching position in which the latch rod engages the slot 87 at the bottom of the slot. After the latch rod has been moved to this latching position, the latch head will cooperate with the arm b of bell crank lever 49 to retain the bell crank levers in their displaced relative positions until the latch is manually raised to restore the levers to their normal positions. The parts are so proportioned that when the bell crank levers occupy their displaced positions, the contacts of both sets S¹ and S² of contacts will be open regardless of the position which the switch or slide bar then occupies.

From the foregoing, it will be seen that a latching device constructed in the manner just described causes the indication contacts of the point detector mechanism to function in accordance with the position of the point detector rod during the time the switch is actually being trailed, rather than after the train has completely trailed through the switch. It will also be seen that this latching device makes it necessary for a maintainer to go to a switch which has been trailed and manually release the latching device before either set of indication contacts can again become closed. It is assumed that when a maintainer goes to the switch to release the latching device, he will inspect the switch points, and if damaged, repair them, thus guarding against a dangerous condition due to damaged switch points.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination with a railway switch and operating mechanism for said switch including a driving member movable between two extreme positions, a motion plate operatively connected with said driving member to move therewith, said motion plate being provided with a cam slot, a pivoted bell crank lever one arm of which is provided with a hole, an eyebolt slidably mounted in said hole and provided at the end opposite its eye with a nut, a compressed coil spring disposed on said eyebolt between said one arm of said bell crank lever and said eye in such manner that said eye-bolt is constantly biased to the position in which said nut engages said one arm, a second lever pivoted intermediate its ends and provided at one end with a pin which receives said eye and at the other end with a cam follower which co-operates with said cam slot, said cam slot being so constructed and the parts being so proportioned that said bell crank lever will be biased to one extreme position by said spring when said driving member occupies one extreme position and will be positively moved to another extreme position by said eyebolt and said nut when said driving member is moved to its other extreme position, a point detector rod secured to said switch to move therewith, means secured to the other arm of said bell crank lever and co-operating with said point detector rod for preventing said bell crank lever from moving to its one extreme position when said driving member occupies said one extreme position unless said switch occupies its corresponding extreme position and the then closed point of said switch is in close engagement with the associated fixed rail, and indication means controlled by said lever.

2. In combination with a railway switch and operating mechanism for said switch including a driving member movable between two extreme positions for moving said switch between its two extreme positions, a bell crank lever, means for operatively connecting said driving member with one arm of said bell crank lever in such manner that said bell crank lever will be biased to one position when said driving member occupies one of its extreme positions, will be positively moved to another extreme position when said driving member occupies its other extreme position, and will be moved to an intermediate position when said driving member is between its two extreme positions, a roller secured to the other arm of said bell crank lever, a point detector rod secured to said switch to move therewith and provided with a notch which aligns with said roller when and only when said switch occupies the extreme position corresponding to said one extreme position of said driving member and the then closed point of said switch is in proper engagement with the associated fixed rail, a pin secured to said other arm of said bell crank lever, a set of contacts each contact of which comprises a fixed contact finger and a movable contact finger, each said movable contact finger being provided with a return bend, and an insulating link provided with a clip having an open end slot which slidably receives the pin on said other arm of said bell crank lever and with a plurality of pins one

of which cooperates with the return bend on each of said movable contact fingers to connect said link with said fingers.

3. In combination with a railway switch and operating mechanism for said switch including a driving member movable between two extreme positions for moving said switch between its two extreme positions, a bell crank lever, means for operatively connecting said driving member with one arm of said bell crank lever in such manner that said bell crank lever will be biased to one position when said driving member occupies one of its extreme positions, will be positively moved to another extreme position when said driving member occupies its other extreme position, and will be moved to an intermediate position when said driving member is between its two extreme positions, a roller secured to the other arm of said bell crank lever, a point detector rod secured to said switch to move therewith and provided with a notch which aligns with said roller when and only when said switch occupies the extreme position corresponding to said one extreme position of said driving member and the then closed point of said switch is in proper engagement with the associated fixed rail, a set of contacts each contact of which comprises a movable contact finger and a fixed contact finger, and an insulating link connected with the movable finger of each contact and with said other arm of said lever, whereby movement of said lever will operate said contacts.
4. In combination with a railway switch and operating mechanism for said switch including a driving member movable between normal and reverse positions for moving said switch between its normal and reverse positions, two pivoted bell crank levers, means for operatively connecting one arm of each lever with said driving member in such manner that the one lever will be biased to a normal position and the other lever will be positively moved to a normal position when said driving member occupies its normal position, that the other lever will be biased to a reverse position and the one lever will be positively moved to a reverse position when said driving member occupies its reverse position, and that both levers will be moved to intermediate positions during movement of said driving member from either extreme position to the other, two rollers one attached to the other arm of said one lever and the other attached to the other arm of said other lever, a point detector rod secured to the switch to move therewith and provided with a notch which receives said one roller when and only when said one lever is biased to its normal extreme position and said switch occupies its proper normal position and which receives said other roller when and only when said other lever is biased to its reverse extreme position and said switch occupies its proper reverse position, latch mechanism connected with said levers in such manner that if said one lever is moved away from its normal position when the other lever occupies its normal position or said other lever is moved away from its reverse position when said one lever occupies its reverse position said latch mechanism will subsequently maintain said levers in displaced relative positions, and indication means controlled by said two bell crank levers.
5. In combination with a railway switch and operating mechanism for said switch including a driving member movable between normal and reverse positions for moving said switch between its normal and reverse positions, a first lever pivoted
- intermediate its ends and provided at one end with a cam follower and at the other end with a pin, a motion plate secured to said driving member and provided with a cam slot which cooperates with said cam follower in such manner that said first lever will be rotated to a normal extreme position, a reverse extreme position, or an intermediate position according as said driving member occupies its normal extreme position, its reverse position, or a position between its normal and reverse extreme positions, two pivoted bell crank levers one arm of each of which is provided with a hole, two eyebolts one slidably mounted in the hole in each lever and each provided at the end opposite to the eye with a nut and each having the eye pivoted on said pin, two compressed springs one disposed on each eyebolt between its eye and the associated arm, and indication means controlled by the other arm of each bell crank lever.
6. In combination with a railway switch and operating mechanism for said switch including a driving member movable between normal and reverse positions for moving said switch between its normal and reverse positions, a first lever pivoted intermediate its ends and provided at one end with a cam follower and at the other end with a pin, a motion plate secured to said driving member and provided with a cam slot which cooperates with said cam follower in such manner that said first lever will be rotated to a normal extreme position, a reverse extreme position, or an intermediate position according as said driving member occupies its normal extreme position, its reverse position, or a position between its normal and reverse extreme positions, two pivoted bell crank levers one arm of each of which is provided with a hole, two eyebolts one slidably mounted in the hole in each lever and each provided at the end opposite to the eye with a nut and each having the eye pivoted on said pin, two compressed springs one disposed on each eyebolt between its eye and the associated arm, and indication means controlled by the other arm of each bell crank lever.
7. In combination with a railway switch and operating mechanism for said switch including a slide bar movable between normal and reverse positions for moving said switch between its normal and reverse positions, a first lever pivoted intermediate its ends and provided at one end with a cam follower and at the other end with a pin, a motion plate secured to said slide bar and provided with a cam slot which cooperates with said cam follower in such manner that said first lever will be rotated to a normal extreme position, a reverse extreme position or an intermediate position according as said slide bar occupies its normal extreme position, its reverse position, or a position between its normal and reverse extreme positions, two pivoted bell crank levers one arm of each of which is provided with a hole, two eyebolts one slidably mounted in the hole in each lever and each provided at the end opposite to the eye with a nut and each having

the eye pivoted on said pin, two compressed springs one disposed on each eyebolt between its eye and the associated arm, whereby the one lever will be biased to a normal position and the 5 other lever will be positively moved to a normal position when said slide bar occupies its normal position, the other lever will be biased to a reverse position and the one lever will be positively moved to a reverse position when said slide bar 10 occupies its reverse position, and both levers will be moved to intermediate positions when the slide bar occupies a position between its normal and reverse position, and whereby both levers will normally be moved in unison during movement 15 of said slide bar from one extreme position to the other, a point detector rod operatively connected with said switch, means secured to said other arm of each lever and cooperating with said point detector rod for moving said one lever 20 away from its normal position if said switch is moved away from its normal extreme position when said slide bar occupies its normal extreme position and for moving said other lever away from its reverse position if said switch is moved 25 away from its reverse position when said slide bar occupies its reverse position, latch mechanism connected with said one arm of each lever in such manner that if said one lever is moved away from its normal position when the other lever 30 occupies its normal position or said other lever is moved away from its reverse position when said one lever occupies its reverse position said latch mechanism will subsequently maintain said arms in displaced relative positions, and indication means controlled by said two bell crank levers.

8. In combination with a railway switch and operating mechanism for said switch including a slide bar movable between normal and reverse 40 positions for moving said switch between its normal and reverse positions, a first lever pivoted intermediate its ends and provided at one end with a cam follower and at the other end with a pin, a motion plate secured to said slide bar 45 and provided with a cam slot which cooperates with said cam follower in such manner that said first lever will be rotated to a normal extreme position, a reverse extreme position or an intermediate position according as said slide bar occupies its normal extreme position, its reverse position, or a position between its normal and reverse extreme positions, two pivoted bell crank levers one arm of each of which is provided with a hole, two eyebolts one slidably mounted in 50 the hole in each lever and each provided at the end opposite to the eye with a nut and each having the eye pivoted on said pin, two compressed springs one disposed on each eyebolt between its eye and the associated arm, whereby 55 the one lever will be biased to a normal position and the other lever will be positively moved to a normal position when said slide bar occupies its normal position, the other lever will be biased to a reverse position and the one lever will be 60 positively moved to a reverse position when said slide bar occupies its reverse position, and both levers will be moved to intermediate positions when the slide bar occupies a position between its normal and reverse position, and whereby 65 both levers will normally be moved in unison during movement of said slide bar from one extreme position to the other, a latch rod pivotally 70

attached to said one arm of said other lever, an open end slot formed in said one arm of said one lever, and a latch head secured to said latch rod and cooperating with said slot in such manner that said latch head will remain in said slot when said levers move in unison, but that, if either lever is moved independently of the other lever said latch head will move out of said slot and will subsequently cooperate with said one arm of said one lever to retain said levers in their 10 displaced relation.

9. In combination with a railway switch and operating mechanism for said switch including a driving member movable between normal and reverse positions for moving said switch between its normal and reverse positions, a first lever pivoted intermediate its ends and provided at one end with a cam follower and at the other end with a pin, a motion plate secured to said driving member and provided with a cam slot which 20 cooperates with said cam follower in such manner that said first lever will be rotated to a normal extreme position, a reverse extreme position or an intermediate position according as said driving member occupies its normal extreme position, its reverse position, or a position between its normal and reverse extreme positions, two pivoted bell crank levers one arm of which is provided with a hole, two eyebolts one slidably mounted in the hole in each lever and each provided at the end opposite to the eye with a nut and each having the eye pivoted on said pin, two compressed springs one disposed on each eyebolt between its eye and the associated arm, whereby the one lever will be biased to a normal 30 position and the other lever will be positively moved to a normal position when said driving member occupies its normal position, the other lever will be biased to a reverse position and the one lever will be positively moved to a reverse position when said driving member occupies its reverse position, and both levers will be moved to intermediate positions when said driving member occupies any position between its normal and reverse position, and whereby both 40 levers will normally be moved in unison during movement of said driving member from one extreme position to the other, a point detector rod operatively connected with said switch, means secured to said other arm of each lever and cooperating with said point detector rod for moving said one lever away from its normal position if said switch is moved away from its normal extreme position when said driving member occupies its normal extreme position and for moving 50 said other lever away from its reverse position if said switch is moved away from its reverse position when said driving member occupies its reverse position, a latch rod pivotally attached to said one arm of said other lever, an open end slot formed in said one arm of said one lever, and a latch head secured to said latch rod and cooperating with said slot in such manner that said latch head will remain in said slot when said levers move in unison, but that, if either lever is moved independently of the other lever said latch head will move out of said slot and will subsequently cooperate with said one arm of said one lever to retain said levers in their displaced relation.
